IGNITION PLUG.

Application filed October 19, 1927. Serial No. 227,094.

This invention relates to electric ignition by the combustion of the fuel which are plugs for use in internal combustion engines transmitted and directed longitudinally for igniting the fuel charge, and it is the object of the invention to provide an ignition plug which is adapted to be utilized as a means for observing the combustion of the fuel in the combustion chamber of an engine.

The inefficiency in operation of internal combustion engines is well known, which inefficiency in operation may be the result of one or more of many causes which are not apparent from an observation of the running of the engines, such as an improper fuel mixture, improper design of the fuel intake manifold drawing an insufficient or improperly mixed fuel charge to certain of the cylinders in multiple cylinder engines, restricted exhaust ports and passages through the manifold leading from said ports, poor and defective ignition, or an unequal compression of the fuel charge. The corrections made for these faults are usually haphazard since the means are not available to the operator for determining which one or more of the numerous causes is lowering the running efficiency of the engines, or whether the engine is operating under maximum efficiency. However, such causes affecting the running efficiency of the engine could be readily ascertained were it possible to observe the combustion of the fuel. It is the object of the present invention to provide an improved constructed and arranged ignition plug for internal combustion engines whereby the combustion of the fuel in the combustion chamber of the engine can be readily observed through the plug and the causes contributing to the inefficient running of the engine ascertained.

Other objects and advantages will hereinafter appear among which is the construction and arrangement of the insulator body and center electrode to compensate for thermal expansion and contraction of the parts.

In carrying out the invention I provide the usual shell electrode adapted for the mounting of the plug in an opening leading to the combustion chamber of an engine, with a center electrode carrying insulator body or core of transparent material, such as glass, mounted in the shell electrode with a portion thereof extended from the shell electrode and exterior of the engine cylinder arranged with a prismatic surface or surfaces whereby the light rays generated

through the transparent insulator body are deflected laterally through the side wall of said body and readily observable, the bore through the insulator body in which the center electrode is carried being preferably arranged with a reflective surface, although this is not absolutely essential, whereby the deflection of the light rays laterally through the side walls of the insulator body is greatly augmented.

In the drawing accompanying and forming a part of this application, Figure 1 is an elevational view of an ignition plug and showing an embodiment of the present invention.

Figure 2 is a longitudinal sectional view of the spark plug shown in Figure 1, and

Figures 3 to 7, inclusive, are elevational views of a series of insulator bodies arranged with different prismatic surface formations to carry out the invention.

The embodiment of the invention shown in Figures 1 and 2 of the drawing comprises the usual shell electrode 8, arranged with an externally threaded portion 9 for threaded engagement in an opening communicating with the combustion chamber of an internal combustion engine, and a sparking terminal 10 fixed in the edge of the threaded end and extending in a direction toward the interior of the threaded portion. The shell is arranged with an internal annular enlargement forming a shoulder 11 for the seating of an insulator body or core 12 of transparent material, preferably of glass, engaged in the shell electrode. An intermediate portion of the insulator body is arranged with an annular enlargement or flange 13, the lower surface of which is adapted to abut the seat 11 and the upper surface engaged by a sleeve or nut 14 threaded into the end of the bore of the shell 8 to secure said insulator body in the shell with an end portion thereof extending beyond the one end of the shell and the opposite end terminating within the shell. The size of the insulator body relative to the shell is such as to compensate for the thermal expansion and contraction of the metal of the shell and of the insulator body to prevent destruction of the latter, as by cracking, and to seal the insulator body in the shell to prevent loss of compression in the engine gas-

kets 15 of the usual type, are interposed be-

tween the flange 13 of the insulator body and the seat 11 and said flange and the securing nut 14.

An electrode in the form of a rod 16 is carried in a bore 23 centrally of the insulator body 12, the bore being of greater diameter than the rod to compensate for expansion and contraction and prevent destruction of the insulator body. The one end of the rod 10 extends beyond the shell adjacent the sparking terminal 10. The opposite end thereof is threaded and extends beyond the insulator for the engagement of a binding nut 17 to secure the terminal of an electric conductor 15 in electrical connection with the center electrode. To prevent longitudinal movement of the rod relative to the insulator body, the rod is arranged with a circular enlargement or shoulder 18 for engagement with a shoulder 20 formed by a recess 19 in the inner end of the insulator body with a washer 20 between the same, said shoulder on the rod being firmly drawn up against the shoulder 25 formed by the recess to seal the end of the bore in the insulator body by a nut 21 engaged on the threaded end of the rod below the binding nut 17. The rod electrode during the combustion of the fuel in the combustion chamber of the engine becomes 30 heated to a very high temperature and to dissipate this heat and prevent injury to the insulator the rod is of greater diameter above the shoulder 17 than below the same, or that portion exposed directly to the heat 35 of combustion, as shown in Figure 2.

To deflect and diverge the light rays of combustion directed longitudinally through the insulator core laterally through the side of the insulator the outer surface of the insulator body is formed as a refractive or prismatic surface or surfaces 22. These surfaces may be formed by cutting or molding the same in the surface of the insulator body and may be of variable formations, as shown 40 in Figures 3 to 7, inclusive. These refractive or prismatic surfaces may be variously formed and disposed in any desired manner about the insulator body and of any predetermined angle. In Figures 1 to 3 they 45 are circularly disposed around and extended radially of the insulator body. In Figure 4 they are in the form of a continuous spiral. In Figure 5 they are in the form of pyramids produced by a pair of spirals one 50 evolved in clockwise direction and the other in anti-clockwise direction and the two intersecting each other. In Figure 6 they are of diamond shape depressed into the surface of the insulator body, and in Figure 7 they 55 are circumferentially disposed around and extend longitudinally of the insulator body.

All of the above designs of refractive surfaces will prove effective in deflecting and diverging the light rays of combustion in 60 a direction laterally of the insulator body.

To augment the deflecting of the said light rays the surface of the bore 23 of the insulator body is arranged with a reflector or mirror surface to reflect the light rays from the center of the insulator body to the outer 70 prismatic surfaces.

It will be seen that the light rays pass up through the transparent body of the insulator and are partially reflected and partially refracted to pass laterally away from the 75 insulator.

Having thus described my invention I claim:

1. In an ignition plug a shell electrode adapted to be releasably mounted in the 80 cylinder of an internal combustion engine, and a center electrode carrying insulator body of transparent material mounted in the shell and arranged with a refractive surface to deflect the light rays generated by 85 the combustion of fuel in the engine cylinder laterally through the insulator body for visual observation.

2. In an ignition plug, a shell electrode adapted to be releasably mounted in the 90 cylinder of an internal combustion engine, a transparent insulator body carried by the shell having an extended portion arranged with prismatic surfaces and a central bore with the surface of the bore forming a reflecting surface, and a rod electrode mounted 95 in the bore of the insulator body.

3. In an ignition plug, a shell electrode adapted to be releasably mounted in the 100 cylinder of an internal combustion engine, a transparent insulator body mounted in the shell with a portion extending beyond one end of the shell arranged with prismatic surfaces to deflect the light rays generated by the combustion of fuel in the engine 105 cylinder and transmitted longitudinally through the insulator body laterally for observation through the side of said body, and a bore extending longitudinally of the insulator, a coating of a reflective material on 110 the wall of the bore, and a rod electrode mounted in and sealing said bore.

4. In an ignition plug, a shell electrode adapted to be releasably mounted in the 115 cylinder of an internal combustion engine, a transparent insulator body having a bore therethrough carried by the shell having a portion extending beyond one end of the shell and the outer surface of said extended portion arranged with prisms, a coating of 120 reflective material on the wall of the bore, and a rod electrode carried in the bore of said insulator body.

5. A transparent insulator body for electric ignition plugs having a bore therethrough and arranged with prismatic surfaces to reflect light rays deflected longitudinally through the body laterally thereof. 125

6. A transparent insulator body for electric ignition plugs as claimed in claim 5, 130

wherein the wall of the bore has a coating of a reflective material applied thereto.

7. A transparent insulator body for electric ignition plugs as claimed in claim 5, 5 wherein the prismatic surfaces are arranged to extend circumferentially around and radially of the insulator body.

8. A transparent insulator body for electric ignition plugs as claimed in claim 5, 10 wherein the prismatic surfaces are arranged in the form of a spiral about the insulator body.

9. A transparent insulator body for electric ignition plugs as claimed in claim 5,

wherein the prismatic surfaces are arranged in the form of spirals evolved in opposite directions about the insulator body and intersecting each other.

10. A transparent insulator body for electric ignition plug as claimed in claim 5, wherein the prismatic surfaces are of diamond shape disposed circumferentially and longitudinally of the insulator body.

Signed at the city of New York, in the county of New York, and State of New York, this 10th day of October, 1927.

HARRY J. LINSE.
